UNITED STATES PATENT OFFICE.

MARK BEADLE, OF BATTLE CREEK, MICHIGAN.

VAPORIZER.

1,242,099.

Specification of Letters Patent.

Patented Oct. 2, 1917.

Application filed March 13, 1916. Serial No. 83,798.

To all whom it may concern:

Be it known that I, MARK BEADLE, a citizen of the United States, residing at Battle Creek, in the county of Calhoun and State 5 of Michigan, have invented certain new and useful Improvements in Vaporizers, of which the following is a specification.

The present invention more particularly relates to means for both accelerating and 10 augmenting the motive or expansive force in internal combustion engines, and it contemplates means whereby a predetermined supply of a substance, as, for instance, water, will be supplied to the combustion chamber 15 of an engine of the class set forth, the same to be supplied independent of the usual fuel supply through a carbureter mixing-valve or other device at every intake stroke of the engine piston and it has, among other objects, to provide a device of the class whereby 20 a greater supply of oxygen may be developed in the combustion chamber simultaneously with the admission of the regular carbureted mixture into the engine cylinder; whereby the formation of carbon may be 25 eliminated in the operation of internal combustion engines; whereby the expansion of gases may be both accelerated and augmented and the ordinary fuel supply reduced to a minimum; whereby the device 30 may be installed on any ordinary internal combustion engine by a mechanic of ordinary ability and at a nominal expense; whereby the same will be simple in construction, compact in form, economical to manufacture and efficacious in operation. These 35 and other objects and advantages will be hereinafter more fully set forth in the following specification and defined in the appended claim.

For the purpose of explaining my improvement in engines of the type set forth, the accompanying drawing illustrates an embodiment of the vaporizer therefor, but 45 the important instrumentalities of the same may be varied, and so it is to be understood that the invention is not limited to the specific arrangement and organization as shown and described.

50 Referring to the drawing: Figure 1 is a broken perspective view of the engine and instrument board of an auto-

mobile with an embodiment of my vaporizer applied to the manifold of the engine.

Fig. 2 is a longitudinal section view of the 55 vaporizer and a broken sectional view of the manifold of an engine to which it is attached, the arrows indicating the flow of the fluids therethrough.

Fig. 3 is a broken longitudinal section, in 60 modification, of the vaporizer air valves and intake port.

Fig. 4 is a perspective view of the valve cage and valve seat.

Fig. 5 is a perspective view of a valve.

Fig. 6 is an outer end view of Fig. 3.

Fig. 7 is a perspective view of the air-regulating screw employed in the modification shown in Fig. 3.

Like marks of reference refer to corresponding equivalent parts in the different views, in which A represents a four-cylinder four-cycle engine *en bloc*; B, the exhaust, C, the manifold from the carbureter; D, the instrument board of an automobile; and E, 70 the vaporizer applied to the manifold for supplying fluid to the mixture emanating from the carbureter.

The vaporizer E comprises, in the main, a conveyance having a longitudinal chamber 1 80 into which a fluid supply tube 2 under control of a valve 3 is connected. The chamber of said conveyance at one end thereof entering the manifold C of an engine is supplied with a porous plug 4, the opposite end of the 85 chamber containing a valve seat 5 and a spring reacting grooved cylindrical valve 6 engaging therewith, the free end of the conveyance having a regulative cap or closure 7 provided with an aperture 8 through which 90 air may enter the chamber 1 of said conveyance.

In the embodiment shown in Fig. 2, the porous plug 4 comprises a basket or container 9 of wire screen having a filling of 95 asbestos or equivalent material, the same being closely fitted within the chamber 1 of the vehicle E and preferably extending into the manifold C between the carbureter and engine so that gases emanating from the carbureter or other supply source of an engine during the intake stroke of its piston will also sweep along the infinitesimal particles of fluid—water for instance—supplied to

said plug from said conveyance. Preferably the chamber in the outer end of the conveyance E is slightly enlarged and bored to form a seat 10 against which the offset end 5 of a valve cage 12 may bear. Within the cage 12 a small valve reacting coil spring 13 and cone-tipped longitudinally-fluted valve 6 is placed, and within the offset ends of the cage side-strips the conically-perforated disk valve-seat 5 is fitted, the arrangement 10 of the parts being such that the conical point of said valve will close the aperture in said valve-seat through action of said spring, and open said aperture for the inflow of air 15 from the exterior by the intake stroke of the engine piston.

An object in assembling the valve, its spring and valve-seat as set forth, is to facilitate the renewal or replacement of the 20 parts as occasion may require.

In Fig. 2, the conveyance E is provided with a screw cap or closure 7 having an aperture 8 through one side thereof, the aperture registering with a corresponding 25 aperture 14 leading from the enlarged end of the chamber 1. The opening formed when the apertures 8 and 14 are coincident permits air to enter the chamber 1 when the valve 6 is unseated, the amount of air 30 being controlled by turning the closure 7 to regulate the size of the orifice between said parts.

In the modified form shown in Fig. 3, the closure 7 has a centrally-disposed screw-threaded opening fitted with a wing thumb-screw 15, an aperture or air reductive passage 16 being formed by cutting away a portion of the threads of both said screw and its opening.

40 The aperture 16 is opened or closed as expedient, by turning said screw to mismatch the cutaway portions of the threads of the respective parts.

The valve-seat 5 in Fig. 3 is held in position 45 between the end of the receptacle E and an offset shoulder 17 in the closure 7, a small chamber 18 being formed between the valve and said closure. In this modification, also, the valve 6 has a stem 19 about 50 which the spring 13 is coiled.

Referring to the valves in question, small longitudinal grooves 20 are formed thereon for the purpose of permitting air to freely 55 flow from the chamber 18 into the chamber 1 when the valve 6 is unseated from its seat 5.

The valve 3 preferably is of needle type, the point thereof being adapted to open and close a passage-way 21 leading from the 60 fluid supply pipe 2 into the chamber 1, the stem of the valve extending diagonally through the instrument board D and fitted with an indicating finger 22 playing over a dial 23 attached to said board. The fluid 65 may be conveyed to the vaporizer E through

one or more pipes leading from one or different sources of supply, a single pipe 2 herein being shown. The pipe 2 may carry a single fluid—as for instance, water from the radiator, water jacket or other water 70 source, to an engine, or it may draw its supply from some wholly independent source, the object of a pipe or pipes being to convey suitable fluid to the vaporizer E, whether from one or more sources, either in 75 simple or compound form.

I will describe the arrangement and operation of the vaporizer as applied to the manifold of a gas engine:

A hole having been drilled and tapped in 80 the manifold C at some place near the exit from the carburetor thereto, the assembled vaporizer E with its externally-threaded end containing the porous plug 4 is screwed therein, and arranged so that the valve stem 85 3 may be readily controlled as, for instance, to operate from a suitable dial on the instrument board D, as shown, and the fluid pipe 2 or pipes connected with some suitable source of supply, as hereinbefore set forth. 90 The vaporizer having been thus installed on an engine, fluid is supplied thereto by opening the valve 3, which permits said fluid to flow from the pipe 2, or pipes, into the chamber 1, from which it enters the porous 95 plug 4 and is drawn from thence into the combustion chamber of the cylinders at the intake stroke of the piston along with the gases from the carburetor with which it affiliates to increase the expansive force of 100 gases thus formed.

If air is desired to accompany the intake of fluid, the cap 7 at the free end of the vaporizer (Fig. 2) is turned to allow the apertures 8 and 14 to register, thereby allowing air to enter the chamber 18 from which it passes through the aperture to the valve seat 5, and about the valve 6 through the grooves 20 and between the basket sides into the main chamber 1 and out through the porous plug 4 into the manifold, the intake stroke of the piston causing a partial vacuum in the chamber 1 thereby releasing said valve 6 from its seat and permitting the passage of air as set forth, the 115 spring 13 causing the valve to reseat.

From the foregoing explanation of the construction and operation of my invention a more extended description, it is believed, will not be necessary.

Having set forth my invention, what I claim and desire to secure by Letters Patent is:—

In a gas engine, a fluid conveyance comprising a barrel open at either end, one end 125 thereof being exteriorly screw-threaded and fitted within a correspondingly-fitted aperture of an engine manifold, the opposite end of the barrel having an enlarged bore and covered with a screw-threaded cap, said cap 130

and said barrel each having an aperture capable of registering by the turning of said cap to admit or prevent air entering said barrel, a cage fitted within said barrel having an offset abutting a shoulder formed between the variable bores of said barrel, a valve seat having an aperture fitted within said offset, a valve fitted within said cage adapted to open and close the aperture in said valve seat, a spring fitted within said barrel adapted to reseat said valve, and a fluid supply pipe opening into said barrel between said manifold and said valve.

MARK BEADLE.
